UNITED STATES PATENT OFFICE.

DEWEY C. DAUBMEYER, OF DETROIT, MICHIGAN.

PLATEN.

Application filed September 28, 1925. Serial No. 59,123.

This invention relates to platens or paper supports and more particularly to combination platens or paper supports adapted for use on adding, accounting, calculating, book-keeping and typewriting machines and the like.

Heretofore the platens or other paper supporting members employed in connection with the various known types of calculating and typewriting machines have been of a uniform surface hardness throughout. If under these circumstances a platen is selected whose surface is relatively hard multi-copy work may be satisfactorily done but when it was desired to make a single copy it was found that the lack of resilience in the platen or paper support resulted in the perforation of the paper or other imprint receiving material and a pitting of the platen by reason of the force of impact of the type. When on the other hand platens having relatively soft surfaces were employed, the perforation of the paper and the pitting of the platen was eliminated but difficulty was experienced in satisfactorily making simultaneously a plurality of copies. Therefore a platen having a uniform surface hardness has been found totally inadequate in multi-copy and single copy work.

Furthermore in machines wherein certain portions of the platen or paper supporting member are employed for supporting a plurality of sheets for multi-copy work while another area of the platen is simultaneously used for supporting a single sheet for single copy work similar difficulties have arisen. If a platen having a surface of a hardness sufficient for multi-copy work, is employed, then that portion used continuously for single copy work becomes pitted and in a relatively short time the platen is unfit for further use. On the other hand if a platen is selected having a relatively soft impact surface the pitting of the platen at the single copy portion is prevented but a plurality of copies cannot be satisfactorily made.

The principal object of this invention therefore is to provide a platen or paper supporting member having areas of different degrees of surface hardness whereby one portion of the platen, which is relatively hard, may be used for multi-copy work; whereas another portion of the platen, which is relatively soft, may be used for single copy work.

The novel features of construction of the invention as well as several illustrative embodiments of the same will be made more apparent as this description proceeds, especially when considered in connection with the accompanying drawings wherein

Fig. 1 is a fragmentary elevational view of an accounting machine with my invention applied thereto,

Fig. 2 is a fragmentary side elevation of the structure illustrated in Fig. 1,

Fig. 3 is an elevational view of the type of platen used in machines such as shown in Figures 1 and 2,

Fig. 4 is a fragmentary elevational view of a well-known type of bookkeeping machine having a platen constructed in accordance with my invention, and

Fig. 5 is a perspective view of the platen embodied in the type of machine illustrated in Fig. 4.

Referring now to the drawings and particularly to Figures 1 to 3, attention is directed to Fig. 1 wherein a conventional form of accounting machine is fragmentarily illustrated, the structure including a frame work consisting of a pair of side frame members 10 adapted to movably support a plurality of rods 11 upon which a pair of paper rolls 12 and a carbon paper roll 13 are mounted. The rolls 12 and 13 are slideable longitudinally of the rods 11 and are secured in their adjusted positions preferably by means of set screws 14.

The frame members 10 are secured to a platen carriage or frame 15 upon which the platen 16 is rotatably mounted. The reference character 17 indicates the banks of type and 18 the hammers, employed in machines of this character, for moving the type into printing relation with the paper.

The platen 16, illustrated more clearly in Fig. 3, has its impact surface thereof divided along the line 19 into two sections 20 and 21. The surface of section 20 is relatively hard so that this portion of the platen may be used for multi-copy work, while the surface of section 21 is relatively soft so that this portion of the platen may be more readily and efficiently used for making single copies. While the surface of the platen herein shown is divided to provide only two portions of relatively different degrees of surface hardness still it will be immediately apparent that it falls within the scope of this

invention to provide additional sections of similar relative degrees or different degrees of surface hardness.

When my improved platen or paper supporting member is associated with a machine of the character herein described and it is desired to make a plurality of copies the rolls 12 and 13 carrying record and carbon paper respectively are adjusted on the bars 11 to substantially the position illustrated in Fig. 1, whereupon the superposed strips of record and carbon papers may be brought around the platen 16 in the manner clearly illustrated in Figs. 1 and 2 and in position to receive the impression from the type of type banks 17 when actuated by the hammers 18. It should be understood that the carriage 15 supporting the platen and the paper roll frame is movable transversely with reference to the type banks 17.

When but a single copy is desired and when consequently a platen having a softer impact surface is desirable, one of the paper rolls 12 may be adjusted to the left hand end of one of the bars 11 and the paper strip therefrom brought around section 21 of the platen 16. The carriage is then shifted to the right as viewed in Fig. 1 so as to bring platen section 21 and the paper supported thereon into register with the key banks 17. If desired an additional paper roll such as indicated at 22 by dotted lines in Fig. 1 may be mounted on one of the rods 11 so as to avoid the necessity of adjusting one of the rolls 12 when a single copy is desired. With such an arrangement it would be only necessary to shift the carriage 15 to bring the paper strip from roll 22 and platen section 21 into register with the key banks.

While the invention has thus far been described as used in connection with machines wherein either multi-copy or single copy records are to be made and wherein only one section of the platen is used at a time, still platens of this character find further utility in machines wherein single and multi-copy records are simultaneously desirable, in which latter instance suitable banks of keys 50 would be brought simultaneously or successively into register with both sections of the platen.

Referring now to Figures 4 and 5 and more particularly to Figure 4, it will be noted that I have illustrated fragmentarily a portion of a bookkeeping machine which includes a frame comprising a pair of side members 25 upon which a platen or paper supporting member 26 is mounted. This 60 platen is in the form of a bed or plate. The frame also provides support for a plurality of rods 27 upon which carbon paper rolls 28 are mounted, this carbon paper being preferably passed around a rod 29 adjacent the rear of the machine and then forwardly

over the platen 26 and between the several superposed sheets of record paper to a clamping bar 30 arranged adjacent the front of the machine. The reference character 31 indicates racks arranged at both sides of the machine upon which the printing mechanism indicated by dotted lines as at 32, travels. In machines of this character the printing mechanism is movable forwardly and rearwardly as well as transversely upon the frame to thus bring same into register with the proper columns on the record sheets supported on the platen 26.

While any number and arrangement of record sheets may be supported upon the 80 platen 26, still in Figure 4 I have shown three record sheets consisting of a principal or ledger sheet 33 and two superposed secondary or bill sheets 34 and 35. Consequently with the arrangement shown three record copies will be made at the area indicated at "A", two record copies will be made at the area indicated by "B" and one copy at the area indicated by "C".

By reference to Figure 5 wherein the platen 26 is illustrated disassembled from the machine it will be noted that the impact surface thereof is shown as formed in three sections 36, 37 and 38. The dividing lines between areas 36 and 37 and between the 95 areas 37 and 38 being indicated by the reference character 39 and being further shown as extending longitudinally thereof. If the platen 26 is to be used most efficiently in connection with the sheets 33, 34 and 35 100 associated in the manner illustrated in Figure 4 then the portion 36 of the impact surface thereof will be relatively hard while those portions indicated by the reference characters 37 and 38 will be successively 105 relatively softer. Consequently area 38 which is the softest portion of the platen will be used to support that portion of sheet 33 upon which a single copy is to be made; area 37 will be used to support superposed 110 sheets 33 and 35 upon which two copies are to be made, and area 36 will support the three superposed sheets 33, 34, and 35 whereon three copies are to be made.

While as an example a platen of the bed 115 or plate type has been illustrated and described as comprising three surfaces of relative degrees of hardness still it will be understood that this is for illustrative purposes only and that this bed type of platen may 120 be provided with only two or any number of sections of relative surface hardness.

As hereinbefore mentioned, the platens 16 or 26 may as desired, be provided with additional sections of different degrees of surface hardness and obviously the platen is not limited in its use to the conventional form of accounting machines herein illustrated, but is equally adapted to various types of accounting, calculating and type- 130

writing machines. The invention therefore should not be limited to the specific disclosures herein contained, reservation being made to make such changes in the details 5 of construction as may come within the purview of the accompanying claims.

What I claim as my invention is:

1. A platen or paper support, the working field of which is divided to provide adjacent 10 relatively hard and soft areas, whereby said platen is adapted for the production of single or multi copies.

2. A platen having a continuous impact receiving surface formed with relatively 15 hard and soft portions, whereby said platen is adapted for the production of single or multi copies.

3. A platen having the working field or surface at one end thereof relatively soft 20 and the working field or surface at the other end thereof relatively hard for single and multi-copy work respectively.

4. A cylindrical platen having an impact receiving surface divided into a plurality of cylindrical sections of relatively different degrees of hardness, whereby the said platen 25 is adapted for the production of single or multi copies.

5. A platen or paper support having a single impact receiving surface smooth 30 throughout the area thereof and divided into a plurality of sections of relatively different degrees of hardness, whereby said platen is adapted for the production of single or multi copies.

6. A platen having an integral impact receiving surface transversely divided into a plurality of sections of relatively different degrees of hardness, whereby the said platen 35 is adapted for the production of single or 40 multi copies.

In testimony whereof I affix my signature.

DEWEY C. DAUBMEYER.
